ROY R. WILEY, OF BUFFALO, NEW YORK.

ILLUMINATED SIGN.

1,123,969.

Specification of Letters Patent.

Patented Jan. 5, 1915.

Application filed July 10, 1913. Serial No. 778,337.

To all whom it may concern:

Be it known that I, Roy R. WILEY, a citizen of the United States, residing at Buffalo, in the county of Erie and State of New York, have invented a new and useful Illuminated Sign, of which the following is a specification.

This invention has reference to improvements in illuminated signs, and more particularly to light transmitting characters for such signs, and its object is to provide a sign character especially adapted for night illumination from the side thereof remote from that observed, but so constructed that light reaching the character from the same side as that observed will be in most part returned to the observer, wherefore the character while brilliantly illuminated at night is also brilliantly illuminated by daylight, the daylight illumination being by reflection, while the night illumination is by transmission and refraction.

In accordance with the present invention the sign characters, although they may be made of any suitable light transmitting medium, are preferably made of glass with the visible side or face of the character in relief and of lens-like cross section so as to be more or less magnifying, while that face of the sign character remote from the observer and which may, therefore, be termed the rear face of the sign character, has a multitude of prisms thereon so arranged that light striking the prisms from either the observed or the rear face of the character is broken up into a multitude of differently directed rays. Such rays traverse the relief face of the character and are sufficiently diverted to be seen by the observer from angles almost, if not quite coincident with the plane of the observed face of the sign.

The outer or visible face of the relief character may be in the form of a group of elongated and substantially parallel partial cylinders coalescing at their meeting edges and conforming to the length of the stroke of the character, or in the case of curved letters having a similar curvature in the direction of the length of such curvature. Such forms are to a greater or less extent lens-like and, therefore, magnifying and are provided with a prismatic backing, so as to become visible both at night and in day time to a marked extent and at great angles of observation.

With a source of illumination directly

back of the sign character thus constructed, whether or not such illuminating source be reinforced by a reflector, and particularly when a light toning-down means is interposed between the source of light and the sign character in the manner set forth in Letters Patent No. 1,081,800, granted to Wiley, Wiley and Hough, Jr., on December 16, 1913, for improvements in illuminated signs, the observer will see an illuminated sign character as though backed up by a source of light as large as the character and without either glare spots or dark spots or lines, the result being due to the coaction of the lens-like or magnifying relief sign stroke backed up by a multitude of prisms, while the daylight effect is particularly brilliant due to the lens-like relief character with the backing of prisms, the surfaces of which prisms are arranged so that great numbers of them totally reflect light entering the letter from the exterior or outer face back through the outer face to the eye of the observer.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation of a portion of an illuminated sign having sign characters constructed in accordance with the present invention. Fig. 2 is a more or less schematic cross section on the line 2—2 of Fig. 1, and drawn on a larger scale. Fig. 3 is a section on the line 3—3 of Fig. 1, omitting distant parts and drawn on a somewhat larger scale than Fig. 1. Fig. 4 is a section similar to that of Fig. 3 but showing a modification. Fig. 5 is a plan view on an enlarged scale of a form of prismatic surface which may be employed.

Referring to the drawings, there is shown a casing 1 provided with openings normally closed by doors 2 each hinged at one edge, usually the upper edge in the installed structure, to such casing, the hinges being indicated at 3, while at the lower edge of the

door there is a fastening device 4 of any suitable character, whereby access to the interior of the sign casing may be had at any time. No showing is made of the interior construction of the casing, since such construction may correspond to the showing of the aforesaid Letters Patent with respect to light giving means, reflecting means, and light toning down means.

10 The doors 2 are customarily made of metal with openings therein conforming to the shape of the sign character, so that only the latter is illuminated by either artificial or daylight.

15 Each sign character is usually independent of the others and is individual to a door. The sign character comprises a glass plate 5 having relief portions 6 thereon rising from the outer face of the plate 5, which may be 20 quite flat, in a manner to be more or less convex, while the rear face of the plate 5 is formed with many prisms 7 so arranged as to in many instances totally reflect to the eye of the observer light reaching them 25 from the front, such light being more or less refracted by the lens-like form of the generally convex raised sign character.

The outer face of the lens-like sign character has the strokes each made of associated elongated partially cylindrical members 8 which may be in parallel relation one to the other throughout any particular stroke, and these cylindrical members are each considerably less than the width of a 35 stroke of a sign character and are grouped together in coalescing relation, following the general curvature of the convexity of the sign character stroke. Such a group of coalescing cylinders forms a multi-lens-like 40 or magnifying surface by which the prismatic surface of the rear face 7 is magnified.

Under some circumstances it may be found to be advisable to produce the strokes 45 of the sign character upon one surface of a glass plate 5^a, as indicated in Fig. 4, with the strokes in the form of partial cylinders 8. In the form shown in Fig. 4 the plate 5^a is backed up by another glass plate 11 on 50 the face of which remote from the plate 5^a there are produced prisms 7, the plates being united in any suitable manner.

The effects produced by the structure of Fig. 4 are similar to those produced when 55 the plate having the character strokes in relief has the rear face prismatic as in Figs. 2 to 5.

Artificial light reaching the rear face of the sign character is broken up into a great 60 number of rays passing to the outer face of the sign character in a multitude of directions and then further diverted by the lens-like construction of the relief face of the sign character. With such construction 65 the effect of the sign character by artificial

light is greatly enhanced and the character is more brilliantly and evenly illuminated than is the case with relief characters having a prismatic backing, but without the magnifying effect, while the appearance of 70 the character is greatly improved, particularly when the strokes are made up of a series of substantially parallel coalescing partial cylinders which extend lengthwise of the character strokes whether such strokes 75 be straight or curved.

The multi-lens-like form of sign character is particularly attractive by daylight, and especially with the prismatic backing such a sign character is strikingly brilliant 80 by daylight and is free from dark spots or lines which are obtrusively apparent in the absence of the prismatic backing. By daylight the light rays entering the outer face of the sign character are reflected back and 85 diverted toward the eye of the observer, so that the character strokes are almost as attractively and brilliantly illuminated as they are at night by artificial light and may be observed from almost any angle, since 90 the daylight effect, especially in direct sunlight, approaches the brilliancy and vividness of appearance produced at night by strong artificial light. This is due both to the prismatic backing which returns the 95 greater portion of the light to the eye of the observer, and to the lens-like form of the character stroke diverting the reflected light at greater angles than would be the case were the character strokes not in relief, or 100 if in relief of some non-magnifying form.

Should dark lines be produced because of out of vision refraction of artificial light, or out of vision reflection of daylight, they are so surrounded by light rays reaching the 105 eye of the observer as to be obliterated by the blending of such surrounding light rays.

The prisms of the prismatic surface may be of various forms and arrangements, but should be relatively small, so that they are 110 not distinctly and individually visible at the usual distance of observation and, moreover, the surfaces of these prisms are arranged at such angles to the front of the sign that with the lens-like relief strokes 115 there are always a multitude of areas of total reflection of light by day light no matter what be the angle of observation with respect to the sign character and by artificial light the light rays are refracted in a multitude of directions and are further diverted or refracted by the lenticular relief surface to cause the sign character to appear to be illuminated from any angle of observation as by a source of light of as great an area 125 as that defined by the outline of the sign character, when in fact sign characters of smaller dimensions require but a single incandescent electric lamp of, say, 25 to 40 watts current consumption when of the character 130

known as tungsten lamps, and only two such lamps for sign characters of relatively large size. By way of example it may be stated that a single 40 watt tungsten incandescent electric lamp is ample for a sign character approximating eight inches in height, or even larger.

The invention is not limited to the use of any specific form of prismatic surface, since the prisms may be regular or irregular, but should in general be of rather small individual size with their faces so related to the visible portion of the sign character as to coact with the lens-like surfaces to produce the desired brilliant effect, especially by daylight, and to produce a great multitude of divergent rays under artificial light.

In Fig. 5 of the drawing there is indicated a form of prismatic surface which may be employed instead of the prismatic surfaces more or less schematically illustrated in the other figures of drawing. In Fig. 5 the prisms are shown as having square bases 25 with regular sloping sides and truncated apices.

By making the relief surface lens-like the character is more clearly defined, since the edges which would otherwise appear more or less ragged, become sharper and clear cut on account of the light being bent into the line of vision at the extreme edges.

What is claimed is:—

1. A sign character of light transmitting material with the visible face having the strokes in relief and formed of coalescing cylindrical lenses elongated in the direction of the strokes of the sign character, and the rear face prismatic and otherwise substantially flat.

2. A sign character of light transmitting material with the visible face of the strokes in relief and formed of coalescing cylindrical lenses elongated in the direction of the length of the strokes of the sign character, and the rear face where visible through the strokes of the sign character prismatic and otherwise substantially flat.

3. A sign character of light transmitting material with the visible face of the strokes of the sign character in relief and formed of coalescing cylindrical lenses elongated in the direction of the length of the strokes of

the sign character, and the surface remote from the visible face backed up by prisms. 55

4. A sign character of light transmitting material comprising a sheet of glass having the strokes of the sign character in relief and made up of cylindrical lenses elongated in the direction of the length of the strokes 60 with the lenses in each stroke arranged in parallelism, and a backing for the glass sheet having the surface remote from the sign character prismatic to provide many reflecting surfaces visible through the strokes 65 of the sign character.

5. A sign character of light transmitting material with the visible face in relief and having the strokes made up of cylindrical lenses elongated in the direction of the 70 length of the strokes and those in each stroke arranged in parallelism, the remote surface of the sign character being prismatic and otherwise substantially flat.

6. A sign character of light transmitting 75 material with the observed or front face having the strokes in relief, and each stroke composed of elongated and substantially parallel coalescing lenses, and the rear face substantially flat and prismatic and composed of a relatively large number of relatively small prisms distributed over said rear face of the sign character and visible through the strokes. 80

7. A sign character of light transmitting 85 material having the strokes in relief and each made up of a plurality of substantially parallel convex ribs coalescing at their long meeting edges, with a substantially flat prismatic face to the rear of the observed face 90 of the sign character, said prismatic face being composed of a relatively large number of prisms of relatively small size as compared with the size of the sign character, and said prisms being distributed throughout the area visible through the strokes of the sign character as seen from the observed face thereof. 95

In testimony, that I claim the foregoing as my own, I have hereto affixed my signature in the presence of two witnesses. 100
